WINDOW INSTALLATION

Charles T. Cresswell, Montreal, Quebec, Canada

Application December 26, 1940, Serial No. 371,707
In Canada July 23, 1940

2 Claims. (Cl. 20—52)

This invention relates to window installations in which the frame and sash elements are made of wood but are clad with metal to render them fire resistant. The sash frames employed in such installations are single glazed and have the wooden rails thereof completely covered by the metal provided for fireproofing purposes. It is also the usual practice to apply the protective metal covering to the wooden window frame so that it covers the indoor as well as the outdoor portions of said frame.

When a wooden window assembly is installed in a wall of a building it frequently happens that the jambs of the window frame are distorted or bowed inwardly to such an extent as to interfere with the free sliding movement of the sashes. This is usually remedied by removing the sashes from the frame and planing down or otherwise trimming the side rails of the sashes so that they will slide freely when replaced in the frame. Occasions also arise where it is necessary to remove the sashes and to plane down or otherwise trim the top and bottom rails so that they will make proper contact with the head and sill members of the window frame.

In the case of the usual fire resistant window installation in which all rails of the wooden sashes are completely encased by the protective metal covering it is not feasible to remove this covering for the purpose of trimming down the wooden rails of the sashes when the sashes have become tight or jammed in the frame due to distortion of the frame by the pressure of the surrounding masonry. With this in mind the metal clad sashes employed in the usual fire resistant window installation are made small enough so that they will still run freely even after the frame has been distorted to a substantial extent by the pressure of the surrounding masonry. In those cases in which interference with the free running of the metal clad sashes is experienced due to excessive distortion of the frame, this condition is simply allowed to continue or is remedied by the substitution of smaller sashes since no adjustment in size can feasibly be made in connection with the sashes originally installed.

The practice of initially making the metal clad sashes sufficiently loose in the frame to allow for the maximum expected distortion of the latter is objectionable since the looseness of the sash is apt to give rise to objectional rattling and other objections.

Another disadvantage of the conventional fire resistant window installations of the type men-

tioned herein is that, owing to the manner in which the metal sheathing is applied to the sashes, they do not lend themselves to the use of double glazed sashes which are frequently required in windows installed in air conditioned buildings and other air conditioned enclosures.

A further objection to the conventional fire resistant window installation is that the application of the metal sheathing so that it extends from the outdoor to the indoor side of the frame and sash elements is undesirable in view of the fact that the sheathing serves as a conductor by which cold is conducted from the outdoor to the indoor side of the window.

15 The main purpose of the present invention is to provide a generally improved fire resistant window assembly in which provision is made for overcoming all of the above mentioned objections. To this end a feature of the invention 20 consists in applying the metal sheathing to the sashes so that suitable portions of the sash rails are left bare and may be planed down or otherwise trimmed to restore the free running condition of the sashes when this condition is interfered with by buckling or distortion of the window frame by the pressure of the surrounding masonry. The method of applying the metal sheathing is also such that bare portions of the bottom rail of the lower sash and the top rail 25 of the upper sash may be trimmed off as required to ensure proper seating of these rails against the frame elements which they engage in their window closing positions.

Another feature of the invention consists in 30 applying the metal sheathing to the component elements of the window frame so that such sheathing will not serve to conduct any appreciable amount of cold from the outdoor to the indoor side of the window.

35 The foregoing, as well as other features and advantages of the invention, will be more readily understood from the following detailed description taken in connection with the accompanying drawings, in which—

40 Fig. 1 is a vertical sectional view of a window installation designed in accordance with this invention.

Fig. 2 is a horizontal section through the sashes and one of the jambs of the window frame, the plane of the section being indicated by the section line 2—2 of Fig. 1.

45 Fig. 3 is a horizontal sectional view showing the application of the invention to a window frame in which mullions are provided.

In these drawings the frame and sash elements

of my improved window installation are respectively indicated at 5 and 6. In the present instance I have shown double glazed sashes each comprising a main frame 7 which carries the outer glazing 8 and a supplementary frame 9 which carries the inner glazing 10. The supplementary frame 9 of each sash is fitted within a recess 11 provided at the inner side of the main frame 7 so that it lies substantially within the thickness of said main frame. The supplementary sash frames 9 may be of the completely removable type disclosed in Canadian Patent 223,345, dated Sept. 5, 1922, and may be temporarily secured in place by the fastening means described in said patent or, alternately, they may be hinged to the main frame and temporarily fastened in closed position as described in my co-pending application Serial No. 324,605, filed March 14, 1940. The outer glazing 8 of each sash 6 is fitted in a recess 12 in the outer side of the main sash frame 7 and is held in place by retaining strips 13. A bent metal strip 14 is applied to each strip 13 to serve as a fire resistant covering for the two sides of the retaining strip that would otherwise be exposed to view. Each protective strip 14 is provided with bent longitudinal edge portions 15 which are hooked into suitable recesses provided in the associated retaining strip 13.

A protective metal strip 17 is also applied to the upper sash 6 to cover the outdoor side and the bottom surface of the bottom rail 6a. A portion 17a of the strip 17 is bent inwardly so that it covers that portion of the upper surface of rail 6a which underlies the lower edge of the outer glazing 8 and the adjacent glazing retaining strip 14. This portion 17a of the protective strip 17 terminates in a downwardly directed portion 17b which is fitted in a groove 6' provided at the sash rail 6a. The protective strip 17 is also provided with a portion 17c which extends upwardly a short distance along the indoor side of the rail 6a and terminates in a bent portion 17d which is in a groove 6'' provided in said rail.

A protective metal strip 18 is also applied to the outdoor side of the top rail 6b of the upper sash. The upper edge of the strip 18 is bent to provide an anchoring portion 19 which is hooked into a recess 20 provided in the outdoor side of rail 6b adjacent the top surface of said rail. The lower portion of the protective strip 18 is bent inwardly as indicated at 21 so that it covers that portion of the bottom surface of rail 6b which lies at the outdoor side of the glazing 8 and is anchored in place by means of a rib-like extension 22 which is seated in a groove provided in rail 6b.

As shown in Fig. 2, protective strips 24, corresponding substantially to the protective strip 18, are applied to cover the outdoor sides of the side rails 6c of the upper sash. Portions 24a of the protective strips 24 applied to the side rails 6c of the upper sash 6 are bent inwardly to cover portions of the sides of the rails 6c which are at right angles to the outdoor side covered by the main portion of the strip 24. These portions 24a are anchored in place by their rib extensions 24b which are fitted in grooves provided in the rails 6c. A protective metal strip 26 is applied to the lower sash 6 to cover the outdoor side of the bottom rail 6d. This strip is provided with a portion 26a and an anchoring rib 26b which correspond, respectively, to the portion 17a and anchoring rib 17b of the protective strip 17 applied to the bottom rail of the upper sash. The strip 26

is also provided with a portion 26c which is bent to extend inwardly across a portion of the lower surface of rail 6d, thence upwardly along the outer wall of the downwardly opening groove 27 and thence inwardly across the top wall of said groove. The groove 27 has a suitable sealing strip 28 fitted therein for sealing engagement with the sill of the window frame.

The side rails 6d of the lower sash have protective metal strips 30 applied to the outdoor sides thereof as shown in Fig. 2. These strips 30 are provided with portions 30a and anchoring ribs 30b which correspond, respectively, to the portions 24a and anchoring ribs 24b of the protective strips applied to the side rails of the upper sash. Each strip 30 is also provided with a portion 30c which is bent inwardly to cover the outer side and bottom wall of a sealing strip receiving groove 31 provided in the jamb opposing surface of the rail 6d.

From the foregoing description it will be seen that all outdoor surfaces of the rails and outer glazing retaining strips of the upper and lower sashes, which would otherwise be exposed to view in the window closing position of the sashes, are covered and effectively protected by the metal sheathing which is applied for fireproofing purposes. It will also be noted that this metal sheathing is applied so that no substantial amount of cold will thereby be conducted from the outdoor to the indoor sides of the sashes. Another advantage of this method of applying the metal sheathing is that it does not interfere with the mounting and fastening of the supplementary sash frames 9 nor with the application of the weatherstripping which is arranged in the bottom groove 27 and in the side groove 31 of the lower sash.

All portions of the window frame 5 which lie at the outdoor side of the lower sash 6 are also rendered fire resistant by the application of suitable metal coverings or sheathings. In this connection it will be noted that the parting strips 33 are covered at the three exposed sides by a bent metal sheathing strip 34, the opposite edges of which are bent to provide anchoring portions 35 which are hooked into suitable recesses provided in the parting strip. The jambs 37 of the window frame are also covered, at the outdoor sides of the parting strips, with metal sheathing strips 38 which are anchored in place in substantially the same manner as described in connection with the previously mentioned sheathing strips. The strips 38 are applied so that they cover the outdoor edges of the jambs, the walls of the jamb recesses 39 in which the sash weights 40 are housed and the outer and bottom walls of the jamb recesses 41 in which the parting strips are fitted. The finishing strips 43 and the molding strips 44 also have their exposed surfaces covered by metal sheathing strips 45 and 46. Similarly, a metal sheathing strip 47 is applied to cover the upper surface 48, the outer edge surface 49 and a portion 50 of the bottom surface of the sill member 51, this strip being secured in place by the bent terminal edges 52 fitted in grooves provided in the sill. Here again it will be noted that the application of the metal sheathing to the component parts of the metal window frame is such that none of the sheathing constitutes a conductor of cold extending uninterruptedly from the outdoor to the indoor side of the window frame. It is true that a portion of the metal sheathing 47 applied to the sill member 51 extends inwardly beyond the indoor side of the

lower sash but this portion of the sheathing is covered by the indoor sill plate 53.

It is important to note that, as clearly shown in Fig. 3, the jamb opposing surfaces of the side rails of both sashes are stepped so that the bare portions of said surfaces are offset outwardly with respect to the metal clad portions of said surfaces. Consequently, it will be seen that it is an easy matter to plane or trim down the projecting bare portions of the jamb opposing surfaces of the sashes to assure or maintain the desired free-running condition of the sashes in the window frame.

In Fig. 3 I have shown a window frame provided with a mullion 54 but it will be noted that the method of applying the metal sheathing to the mullion is substantially the same as the method followed in applying the sheathing to the window frame jambs as shown in Fig. 2.

It will be understood that the present invention is not limited in its application to windows of the sliding sash type but may also be embodied in casement type windows in which the sashes are hingedly or swingably mounted, or in any other type of windows to which it may be adapted. It will also be understood that the top rail of the upper sash shown in the present drawings may be provided with a sealing strip receiving groove for the reception of a sealing strip adapted to engage the top portion of the window frame.

In addition to the advantages previously men-

tion, the herein described method of constructing the window sashes is such that the provision of suitable sealing receiving grooves in the window frame engaging surfaces of the sash rails 5 may be accomplished without encountering the difficulties experienced in providing for proper sealing of the window when the sash rails are completely encased in metal sheathing.

Having thus described my invention, what I 10 claim is:

1. A window sash having its outdoor side completely covered by metal sheathing, edge portions of which are bent around the side rails of the sash and hooked into recesses provided in 15 the jamb opposing surfaces of said rails, said recesses being located closer to the outdoor than to the indoor side of the sash, those portions of the side rails which lie at the indoor side of said recesses being of such width as to present bare 20 jamb opposing surfaces which project beyond the sheathing covered jamb opposing surfaces which lie at the outdoor side of said recesses.

2. A window sash provided with side rails having stepped jamb opposing surfaces, each surface being so stepped that a portion thereof immediately adjacent the outdoor side of the sash is offset inwardly with respect to the remaining portion thereof and metal sheathing covering the 25 outdoor sides of the sash rails and the inwardly offset portions of said jamb opposing surfaces.

CHARLES T. CRESSWELL.
